**STRUCTURAL CLAMP SUPPORT FOR I-BEAMS,
ANGLES, AND THE LIKE TO SUPPORT CON-
DUITS, HANGERS, SCAFFOLDS, TIEDOWNS
AND THE LIKE**

Joseph E. Dorris, 405 Auburn Drive,
Lafayette, La.

Filed Aug. 13, 1968, Ser. No. 13,126

Term of patent 14 years

Int. Cl. D8—03

U.S. Cl. D8—235

FIG. 4

FIG. 5

FIGURE 1 is a side elevation of a structural clamp support for I-beams, angles, and the like to support conduits, hangers, scaffolds, tiedowns and the like, showing my new design, the side not shown being identical to that side shown.

FIGURE 2 is a top view.

FIGURE 3 is a bottom view.

FIGURE 4 is a left-hand elevation view.

FIGURE 5 is a right-hand elevation view.

I claim:

The ornamental design for a structural clamp support for I-beams, angles, and the like to support conduits, hangers, scaffolds, tiedowns and the like, substantially as shown and described.
